UNITED STATES PATENT OFFICE.

JOSEPH P. McHUGH, OF NEW YORK, N. Y.

DESIGN FOR FABRIC FOR HANGINGS, PORTIÈRES, &c.

SPECIFICATION forming part of Design No. 27,965, dated December 7, 1897.

Application filed May 28, 1897. Serial No. 638,630. Term of patent 7 years.

To all whom it may concern:

Be it known that I, JOSEPH P. McHUGH, a citizen of the United States, residing at New York, in the county of New York and State 5 of New York, have invented and produced a new and original Design for a Fabric; and I do declare the following to be a full, clear, and exact description of the same, reference being had to the accompanying drawings, 10 forming a part thereof.

The object of my invention is to produce a new and original design for fabric for hangings, portières, and the like.

Figure 1 is a plan view of the right side of 15 the fabric, showing my new design. Fig. 2 is a section taken on line X X of Fig. 1. Fig. 3 is a plan view of the wrong side of the fabric.

As shown in the drawings, the leading and material feature of my design consists of a 20 series of horizontally-disposed bands A, separated at a distance from each other, which bands are each made up of vertical convolu-

tions of a cord B, said convolutions united by smaller longitudinal cords C, and a series of vertical and parallel connecting-cords D, 25 arranged in groups of four, and said groups separated from each other, the distance of said separation being such as to leave rectangular openings in the fabric, bounded on the top and bottom by parallel bands and on 30 the sides by oppositely-disposed groups of connecting-cords, the general appearance of the fabric being that of open checker-work.

Having thus described my invention, what I desire to claim as new is—

The design for a fabric as herein shown and described.

In testimony whereof I affix my signature in presence of two witnesses.

JOSEPH P. McHUGH.

Witnesses:

CHAS. M. HEYMANN,
GEO. N. FELLOWS.
